UNITED STATES PATENT OFFICE

GEORGE WESP, OF NEW YORK, N. Y., ASSIGNOR TO THE ROSENTHAL CHINA CORPORATION, OF NEW YORK, N. Y., A CORPORATION OF NEW YORK

DESIGN FOR A PLATE OR SIMILAR ARTICLE

Application filed June 10, 1932. Serial No. 44,040. Term of patent 3½ years.

To all whom it may concern:

Be it known that I, GEORGE WESP, a citizen of Germany, and an applicant for citizenship of the United States, residing in New York city, county and State of New York, have invented a new original, and ornamental Design for a Plate or Similar Article, of which the following is a specification, reference being had to the accompanying drawing forming a part thereof.

The figure is a top plan view of a plate, showing my new design. The ornamentation appearing in the drawing is continued throughout the border of the plate.

The shading in the drawing represents the design in relief.

I claim:

The ornamental design for a plate or similar article as shown, and described.

GEORGE WESP.
